ATTORNEYS.

UNITED STATES PATENT OFFICE.

WILLIAM J. TURL, OF NEW YORK, N. Y., ASSIGNOR TO JOHN TURL & SONS,
OF SAME PLACE.

SHEET-METAL MANTEL.

SPECIFICATION forming part of Letters Patent No. 374,718, dated December 13, 1887.

Application filed June 20, 1887. Serial No. 241,875. (No model.)

To all whom it may concern:

Be it known that I, WILLIAM J. TURL, of the city, county, and State of New York, have invented new and useful Improvements in 5 Sheet-Metal Mantels, of which the following is a full, clear, and exact description.

This invention relates to mantels or mantel-pieces struck up or formed in sheet metal and built up in sections; and it consists in certain 10 special constructions of the parts, substantially as hereinafter described, and pointed out in the claims.

Reference is to be had to the accompanying drawings, forming a part of this specification, 15 in which similar letters of reference indicate corresponding parts in all the figures.

Figure 1 represents a front elevation of a sheet-metal mantel-piece embodying my invention. Fig. 2 is a vertical section of the 20 same upon the line $x x$ in Fig. 1, and representing it as in position relatively to the wall of a room or fire-place therein. Fig. 3 is a further vertical section in part upon the line $y y$ in Fig. 1. Fig. 4 is a horizontal section on 25 a larger scale, upon the line $z z$ in Fig. 1, through one of the pilasters, its facing, and wall-plates. Fig. 5 is a view in perspective of a portion of the mantel-shelf. Fig. 6 is a perspective view of a portion of the frieze, 30 and Fig. 7 is a perspective view of a portion of one of the pilasters with its facing and wall-plates.

Before describing the several parts I would here observe that the same are not restricted 35 to any particular design or ornamental configuration, as such may obviously be changed to suit different demands or tastes.

A is the frieze of the mantel, made of sheet metal stamped up to shape in dies, and all in 40 one piece throughout its length, and separate from the pilasters. Said frieze is constructed to form end wall-plates, $b b$, an upper inner rolled-over flange or support, c , for the shelf of the mantel, and opposite end portions, $d d$, 45 arranged to stand out in line with the pilasters and formed to present hollow bead-like stiffening projections $e e$ at their lower ends, said projections also serving to cover or give a finish to the joint where the end portions, 50 $d d$, of the frieze lap over the pilasters.

B B indicate the pilasters, $f f$ the side fac-

ings thereto, and $g g$ the wall-plates thereof, all made in one piece by being rolled or stamped out of sheet metal, and preferably made with a fluting and set-off, h , at their lower ends. 55 These pilasters, with their attached facings and wall-plates, are fitted under and so as to be overlapped by the end portions of the frieze A, as shown in Fig. 1, and are united with the frieze by rivets or solder.

C is the shelf of the mantel, which is also a separate piece, made of sheet metal, and is rolled over on its inner longitudinal margin, i , where it enters and engages with the wall, and its remaining margins, including its front 65 overhanging longitudinal one, k , bent down to give finish and strength. This shelf is united with the upper inner flange, c , of the frieze, on which it rests, by rivets, bolts, or otherwise.

Thus constructed, the sheet-iron mantel forms a cheap, light, and ornamental structure; but I propose to further ornament it, when desired, by perforating its frieze, pilasters, or either, according to any desired design and in any number of places, and to fill 70 said apertures with projecting ornaments l , made of glass, porcelain, or other suitable material, and of any desired shape or pattern. These ornaments may be secured within the 75 apertures made to receive them by pressing them to their places therein and fastening them by rings, or, as shown in Fig. 4, by turning the marginal portion m of each receiving-aperture backward and inward or over to give strength, 80 and snapping or springing the ornament l to its place therein.

In some instances the parts of the mantel will be sold separately, so that injured parts may be replaced or a frieze of one configuration be substituted in lieu of another of less desirable or preferred design.

Having thus fully described my invention, I claim as new and desire to secure by Letters Patent—

1. In a sheet-metal mantel of the character described, a separate and independent frieze formed of a single piece of sheet metal having an inward-projecting flange or shelf-support, c , along its upper edge, and integral downward-projecting end portions, d , substantially as set forth.

2. In a sheet-metal mantel, a separate and independent frieze struck up from a single piece of sheet metal and formed with the downward-projecting end pieces, *d*, having stiffening projections *e* at their lower ends, and the separate sheet-metal pilasters, the joints between which and the frieze are concealed by said end pieces, *d*, and their stiffening projections, substantially as set forth.
- o 3. A sheet-metal mantel comprising the sheet-metal frieze *A*, all in one piece, with an inner upper longitudinal flange or shelf-support, *c*, and downwardly-projecting front end

portions, *d*, the sheet-metal pilasters *B*, with the facings *f* and wall-plates *g*, integral with *B*, the pilasters, all united with the frieze, and the separate sheet-metal shelf *C*, united with the flange *c* of the frieze, and having its exposed marginal portion or portions turned down, as at *k*, essentially as shown and described.

WILLIAM J. TURL.
